CLAIM

The ornamental design for a needle for a timepiece, as shown and described.

DESCRIPTION

FIG. 1 is a perspective view of a needle for a timepiece, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front elevation on a reduced scale of the needle for a timepiece shown with unclaimed environmental structure.

The broken lines in FIG. 8 are for illustrative purposes only and form no part of the claimed design.
